UNITED STATES PATENT OFFICE.

EDWARD PIEPENBRING, OF WASHINGTON, DISTRICT OF COLUMBIA.

DESIGN FOR AN ORNAMENTAL FRAME FOR TEAPOTS OR SIMILAR ARTICLES.

SPECIFICATION forming part of Design No. 35,924, dated May 27, 1902.

Application filed December 7, 1901. Serial No. 85,100. Term of patent 3½ years.

To all whom it may concern:

Be it known that I, EDWARD PIEPENBRING, a citizen of the United States, residing at Washington, in the District of Columbia, have invented and produced a new and original Design for Ornamental Frames for Teapots or Similar Articles, of which the following is a specification, reference being had to the accompanying drawings, forming part thereof, and in which—

Figure 1 is an elevation of one side of a frame, showing my new design; and Fig. 2 is an elevation of the opposite side of the frame, showing my new design.

15 The leading feature of my design consists in the design forming the subject-matter of the accompanying illustration.

The frame embraces the teapot and has on one side the holly-sprays A A, whose stems a 20 cross each other, the sprays being disposed to form an open wreath and being jeweled at A' in the similitude of the holly-berries. The wreath-sprays A A are connected by chains B B' with the top and base rings C C', which

encircle the teapot, as shown, and are connected on the opposite side of the teapot from the holly wreath by means of ornamental scrolls D D' with the top and base rings, the scrolls D D' being arranged to form edge ornate- 25 ments for the rings C C' and to encircle a shield-like figure E, arranged on the opposite side of the teapot from the holly wreath, as will be understood from Figs. 1 and 2.

Having described my invention, what I 35 claim as new, and desire to secure by Letters Patent, is—

The design for an ornamental frame for teapots or similar articles, as herein shown and described.

40 In testimony whereof I have signed my name to this specification in the presence of two subscribing witnesses.

EDWARD PIEPENBRING.
